UNITED STATES PATENT OFFICE.

FRANCIS E. STEVENSON, OF MOUNT GILEAD, OHIO, ASSIGNOR TO THE HYDRAULIC PRESS MANUFACTURING COMPANY, OF MOUNT GILEAD, OHIO.

DUPLEX PUMPING ENGINE.

Application filed February 19, 1921. Serial No. 446,260.

To all whom it may concern:

Be it known that I, FRANCIS E. STEVENSON, a citizen of the United States, residing in Mount Gilead, in the county of Morrow and State of Ohio, have invented certain new and useful Improvements in Duplex Pumping Engines, of which the following is a specification.

This invention relates to duplex pumping engines of the kind in which a plurality of pumps are each operated by a steam engine and are so actuated as to maintain a continuous flow of water through the supply pipes free from concussion or shocks. Such duplex pumping engines have heretofore been so constructed that each engine is capable of operating its own steam valves, either separately or together with the valves of the other engine, so that each engine can be worked separately when for any cause the steam engine or pump of the other set is not in working order, or both engines may be operated in unison.

According to my invention I provide an improved valve gear whereby the steam valves of each engine are actuated by the other engine when geared for conjoint operation and the construction is also such that if either engine is disabled the other engine, by a slight change in the mechanism, may be made to operate its own valves while the disabled engine remains at rest.

My improved valve gear is especially designed for use in pumping engines employing the well known Burnham or Dean valves, in which an auxiliary valve actuated from the pump cross head is employed to control the steam admission to a piston valve, which in turn operates the engine slide valve.

In the accompanying drawings,

Figure 1 is a plan view of a duplex pumping engine showing the steam cylinders and the valve mechanism thereof, the pumps being omitted;

Figure 2 shows a side elevation of the parts shown in Fig. 1;

Figure 3 is a local section on the line 3—3 of Fig. 2;

Figure 4 shows a side elevation of the valve mechanism employed when only one of the pumps is operated;

Figure 5 is a plan view of the mechanism shown in Figure 4;

Figure 6 shows a vertical section of parts

of a Burnham valve employed in the steam engines;

Figure 7 shows a horizontal section of a Burnham valve;

Figures 8 to 14, inclusive, are perspective views of different parts of the mechanism employed in my improved valve gear.

Two steam engine cylinders A and B, of well-known construction, are supported on a bed-plate C. Each cylinder is equipped with Burnham valve mechanism D, to which steam is admitted at d and from which steam is exhausted at d'. It will be understood that the Burnham valve comprises, briefly stated, a slide valve e, which is operated by a double piston valve e', to which it is directly connected at e². The piston valve is operated by steam admitted by suitable ports controlled by an auxiliary valve f, to which is connected a valve rod F, actuated in the manner hereinafter described. Each of the cylinders A and B is equipped with a Burnham valve of the kind above described and shown more in detail in Figures 6 and 7. It will be understood, however, that my improvements may be applied to other kinds of valves, but the mechanism specifically shown in the drawings is especially adapted to operate in connection with Burnham or Dean valves, and as these are of well-known construction the manner in which they operate need not be here described.

The inner cylinder head of each steam engine is attached to the ends of four frame bars G, which in practice extend to the pump with which the engine is associated, but which is not shown in the drawings. Each steam engine piston rod H reciprocates in the space between the four frame bars and each piston rod carries a cross head K, provided with a headed pin k.

The valve rods F of the Burnham valves are operated in the manner soon to be described, observing first, however, that the valve rod of one engine is operated from the piston rod of the other engine. Neither engine operates its own valves when working on the duplex principle.

The valve-operating mechanism of each engine is of substantially the same construction. As shown in Figures 1, 2 and 3, one of the frame bars G on each side of the engine carries a frame L and a bracket L',

which are clamped to the frame bar by bolts l , as shown in Figures 2 and 3. The arms M , M' of the frame L have bearings for two rock-shafts N and O , which extend 5 from the arms of the frame L on one side of the engine to the corresponding arms on the opposite side thereof, as shown in Figure 1. Each bracket L has a part P , formed with a hole p , through which a 10 valve rod F extends, and in which it is guided, and said part P is also formed with a guide q , in which operates a valve rod actuating device Q , which, as shown, is in the form of a cylindrical block. The 15 opposite ends of the block Q are adapted to engage nuts r , r' , on the screw-threaded portion of a valve rod F .

As viewed from the upper side of Figure 1, the engine A is on the left-hand side of 20 the duplex pumping apparatus and the engine B on the right-hand side thereof. The end of the rock-shaft O on the left-hand side of the engine has keyed or otherwise secured to it an arm S , the outer end 25 of which is pin-jointed at s to a link S' , in turn pin-jointed at t to the outer end of a lever T , pivoted at t' to the bracket L' , and having a slotted end t^2 engaging the cross head pin h .

30 The rock-shaft N in like manner carries an arm S^2 , connected by a link S^3 with a lever T^2 , similar in all respects to the lever T and having a slotted lower end connected with the cross head pin h of the right-hand engine. The rock-shaft N has secured to 35 its left-hand end a cam U , having a cam-slot u , into which projects a roller u' , carried by a pin u^2 , carried by the cylindrical block Q . The pin u^2 is connected to the 40 block Q by a squared part u^3 , operating in a guide slot in the cam U , in such manner that the roller is made to move in a straight path while freely revolving about its pin support.

45 In a similar way the rock-shaft O has secured to it a cam U^2 , connected to the block Q in the manner just described.

It will be observed that the connections 50 between the links S' , S^3 , and the arms S and S^2 , are detachable and the cams U , U^2 are also detachably connected with the rock-shafts N and O .

When both engines are operating the cross 55 head of engine A through the lever T , link S' , arm S and rock-shaft O , operates the cam on the right-hand side of the engine and in like manner the cross head pin of the engine B operates by means of the lever T^2 , link S^3 , arm S^2 and shaft N , the cam U on the left-hand side of the engine. Each 60 cam operates its roller u' , giving movement to a block Q , which strikes against the nuts r , r' , and thus operates the auxiliary valve f of the engine with which it is connected.

65 The cam slot of each cam U , U^2 is of

course properly shaped, as shown, to move the valve operating device Q at the proper intervals and to the proper extent and the cross heads K and the mechanism operated thereby are also properly disposed, as 70 shown, to cause the engine to operate properly when working together.

When the engines are operating together there should be some lost motion during 75 each part of the stroke of the pump. The steam valves, the cams and the other mechanism shown are suitable for this purpose. Obviously, however, the mechanism may be of such kind as to operate without the lost motion referred to.

Should one of the engines become disabled, the other would be put out of operation also. In such case provision is made for 80 operating the companion engine. To do this the slotted cam of such engine is detached from its rock-shaft and is replaced by a slotted cam U^4 , as indicated in Figure 85 4, having a cam slot u^4 , suitably shaped to operate the engine with which it is associated, without in any way disturbing the 90 disabled engine. Assuming that the right-hand engine is disabled, its link S^3 should be disconnected from the arm S^2 and the link S' should be disconnected from the lever T . The arm S^2 should be slid to the 95 left-hand end of the rock-shaft N and the link S' swung over and connected to said arm S^2 . When thus connected the left-hand engine can operate alone, while the other engine is undergoing repairs. The link S^3 100 may be allowed to drop and remain idle while still connected to the lever T^2 . When the engine B is put in working order the necessary parts may be shifted and again connected in the manner before described and as shown in Figures 1 and 2.

It will thus be seen that by a very simple mechanism provision is made for operating the duplex pumps in perfect harmony, the mechanism being of simple construction and 110 of such nature that should one of the pumps become disabled the operation of the other pump may be continued without delay.

I claim as my invention:

1. In a duplex pumping engine, the combination of the engine cylinders, valves and piston rods of a cross head carried by each piston rod, a valve rod for each engine, rock-shafts extending from one engine to the other, a lever operatively connected with each cross head, a link jointed to each lever and detachably connected therewith, an arm on each rock-shaft and mounted to slide thereon, a detachable connection between each arm and a link connects it with a lever, a cam detachably connected with each of said rock-shafts, and connections between each cam and a valve rod.

2. In a duplex pumping engine having two steam cylinders with their pistons and

piston rods and valves, the combination of valve rods connected to said valves, and connecting means between the piston rods and valve rods, said means being settable in two 5 different positions, in one of which the piston rod of each engine operates only the valve rod of the other engine, and in the other of which, the piston rod of each engine operates only its own valve rod.

10 3. In a duplex pumping engine having two steam cylinders with their pistons and piston rods and valves, the combination of valve rods connected to said valves, and a train of connections between each piston rod 15 and the valve rod of the other engine, an element of each train of connections being adjustable to a second position in which it may be connected to the opposite train of connec-

tions, so that the piston rod of either engine will operate only its own valve rod. 20

4. In a duplex pumping engine having two steam cylinders with their pistons and piston rods and valves, the combination of valve rods connected to said valves, and a train of connections between each piston rod 25 and the valve rod of the other engine comprising a rock shaft, an element of each train of connections being slideable along said rock shaft to a second position in which it may be connected to the opposite train of 30 connections, so that the piston rod of either engine will operate only its own valve rod.

In testimony whereof, I have hereunto subscribed my name.

FRANCIS E. STEVENSON.
